UNITED STATES PATENT OFFICE.

CHARLES E. ADAIR, OF BUFFALO, NEW YORK, ASSIGNEE TO CYPHERS INCUBATOR COMPANY, OF BUFFALO, NEW YORK, A CORPORATION OF NEW YORK.

INCUBATOR.

938,200.

Specification of Letters Patent. Patented Oct. 26, 1909.

Application filed January 22, 1906. Serial No. 297,117.

To all whom it may concern:

Be it known that I, CHARLES E. ADAIR, a citizen of the United States, and resident of Buffalo, in the county of Erie and State of New York, have invented certain new and useful Improvements in Incubators, of which the following is a specification.

This invention relates to incubators, and consists in the apparatus hereinafter described and claimed.

In the drawings:—Figure 1 is a front elevation of a device embodying this invention; Fig. 2 is a horizontal section on the line 2—2 of Fig. 1; Fig. 3 is a vertical section on the line 3—3 of Fig. 1; Fig. 4 is a front elevation of a modified form of the invention; Fig. 5 is a horizontal section on either of the lines 5—5 of Fig. 4; and Fig. 6 is a vertical section on the line 6—6 of Fig. 4. Figs. 7 and 8 are vertical sections of a supplementary jacket and part of a lateral air conduit having modified forms of damper devices.

The main purpose of this invention is to provide a large incubator device capable of hatching large numbers of eggs, which is divided into compartments, each capable of control independently of the others, but all fed with heat preferably from a common source of supply, and provided with circulating means that is common to all compartments but independent as to each.

In the device illustrated in Figs. 1, 2 and 3, the several compartments are fed with heated air for producing the heating of the egg chamber, and the air is exhausted or led away by a separate outlet duct for each compartment. In the form of device shown in Fig. 1, there are four compartments 1, 2, 3 and 4, each having its own door 5, 6, 7 or 8.

Each compartment is divided into two portions by a horizontal porous diaphragm 9, separating the upper or heating chamber 10 from the lower or egg chamber 11. The egg chamber 11 contains one or more egg trays 12 supported therein at a suitable height from the bottom of the compartment, and in the lower part of each compartment, underneath the egg tray or trays, is one or more air outlets 13. The heating chamber 10 is provided with a heating box 14, having means of circulating a heating fluid therein, which fluid in the present case is hot air. This air is brought into the box 14 through the induction or inlet flue 15, which divides

in the transverse spreading flue 16. The ends of the transverse flue 16 are continued in the lateral flues 17, from the ends of which the air escapes into the chambers 18 and passes out by means of the outlet flues 19. The heating fluid or hot air is brought in by the common trunk or main 20, having the vertical connecting flues 21 for carrying the heating fluid from the main to the compartments situated above each other. The inlet flue 15 for each compartment or heating box is connected with a vertical flue 21, and in one example of this invention extends into the said vertical flue, and is provided with automatic means for cutting off the heating fluid from the compartment comprising a suitable valve, such as the valve 22 hinged in proximity to the beveled end 23 of the inlet flue. The end of the flue is so beveled as to have a downwardly-directed opening, and the valve is so hung that the air rising in the flue will be deflected from the face of the valve into the end of the flue. Each valve 22 is suitably connected to a balanced lever or bar 24 conveniently placed upon the top of the compartment to which it relates, suitably pivoted on a support 25, and having a counterbalance weight 26. The lever or bar 24 is connected to a rod 27, which extends into the compartment, and is adapted to be operated by a suitable thermostatic device 28 in the egg chamber 11. By this means, as the temperature in the egg chamber rises, the valve 22 will move toward the closed position, cutting off to greater or less degree, or entirely, the inlet of heating fluid through the inlet flue 15.

The outlet flues 19 are connected with an outlet main 29 conveniently by vertical pipes 30 to which the said outlet flues connect directly. In the form of device shown in Figs. 1—3, there are two outlet flues 19 for each inlet flue 15 for the purpose of causing an even distribution of the heated air throughout the heating box 14. The combined areas of the cross-sections of the outlet flues equal the area of the cross-section of the inlet flues.

The inlet main 20 is connected with a proper source of heat, which may be an ordinary hot air furnace, and the outlet main 29 is carried to the outer air.

A supplementary jacket 31 surrounds the vertical flue 21 adjacent to each heating

chamber 10. This jacket 31 is closed at its top 32, and has a ventilating conduit or fresh air duct 33 leading into the heating chamber 10 beneath the heating box 14. The flue 21 carrying heated air will, by radiation, heat air in the space between the jacket 31 and said flue 21, and the air thus heated will rise and pass through the duct 33 into the heating chamber 10, downward through the porous diaphragm 9, through the egg chamber 11, and out through the air outlets 13. Thus a constant movement of air through the egg chamber 11 is provided for.

It will be noted that the volume of air that may pass into the heating box 14 from the main 20, and thence through the outlet pipes and main 29, may be very considerable, and consequently the air passing through the heating box 14 in great volume will not need to be highly heated in order to communicate sufficient heat to the egg chamber 11. Only such a degree of heat is necessary in the box 14 as will by the radiation therefrom, and by the inlet of heated air through the fresh air duct 33, keep the temperature of the egg chamber at the required point, namely; at about 103° F. By this device a continuous current of sufficiently heated air is passing through the box 14, and the inlet of air to each such box is independently controlled by the thermostatic arrangement and valve belonging to that compartment. When the temperature in a compartment rises too high, the valve 22 is closed and the inlet of heat is cut off, but the chilling of that compartment by too rapid ingress of cold air is not possible because, when the valve 22 is closed, the air remains substantially immovable in the box 14, and said box will cool down gradually without causing any too great indraft of cold air into the egg chamber through the duct 33. As soon as the egg chamber cools down to a proper degree the valve 22 will open and the heating of the box 14 will be resumed. These operations as to any one compartment do not affect any other compartment.

In the form of device shown in Figs. 4, 5 and 6, a hot water or steam circulation system is substituted for the box 14, although in all the cases a fluid is employed for producing the heating, and said fluid is conducted through radiating conduits in the upper part of each compartment and above the porous diaphragm 9. In this case the inlet main 35 is provided with lateral connections 36, each controlled by a valve 37, to a radiating conduit, consisting of the pipes 38 in the heating chamber 10 of each incubator compartment. These pipes are attached at their outlet ends by connections 39 with return or outlet pipes or mains 40. A supplementary jacket 41 is provided around the connections 36 and 39, which are preferably vertical, and this jacket is closed at its top 42, except as hereinafter described, and is provided with the lateral air conduit 43 extending into the heating chamber 10 above the diaphragm 9, so that air may enter the open bottom of the jacket 41, and, being heated by the pipes 36, 38 and 39, is delivered into the heating chamber 10 in a warm condition, and may then pass downward through the diaphragm 9 to the egg chamber 11 and out through the air outlets 13. Each jacket 41 is provided with a damper 44, which may be opened when the form is that shown in Fig. 6, to allow air to pass up through the jacket 41 and out through the top of said jacket when said damper 44 is open, but when said damper is closed, air passes into the heating chamber 10 through the conduit 43. The damper 44 is connected to a lever or bar 24 of the same construction and is operated in exactly the same manner as has been just described.

In Figs. 7 and 8 are shown valve devices that are equivalents of those shown in other figures.

What I claim is:—

1. In combination with an incubator divided into multiple compartments, of a common main for delivering heating fluid; a radiator in each compartment having a connection with said main; a ventilating duct for each compartment adapted to discharge therein fresh air adjacently to a radiator; means for choking back around the radiator, the fresh air admitted through said ducts; substantially as shown and described.
2. In combination with an incubator divided into multiple compartments, of a common main for delivering heated fluid; a radiator in each compartment having a connection with said main; a ventilating duct for each compartment adapted to discharge therein fresh air adjacently to a radiator; means for choking back around the radiator, the fresh air admitted through said ducts; and independent means for each compartment for controlling the diffusion of heat therethrough; substantially as shown and described.
3. In combination with an incubator divided into multiple compartments, of a common main for delivering heating fluid; a radiator in each compartment having a connection with said main; a ventilating duct for each compartment adapted to discharge therein fresh air adjacently to a radiator; means for choking back around the radiator, the fresh air admitted through said ducts; and independent means for each compartment for controlling the supply of fluid to its radiator in accordance with the temperature of each compartment; substantially as shown and described.
4. In combination with an incubator divided into multiple compartments, of a com-

mon main for delivering heating fluid; a radiator in each compartment having a connection with said main; a common discharge main; a connection from said discharge main to each compartment; a ventilating duct for each compartment adapted to discharge therein fresh air adjacently to a radiator; and means for choking back around the radiator, the fresh air admitted through said ducts; substantially as shown and described.

5. In combination with an incubator divided into multiple compartments, of a common main for delivering heating fluid; a 15 radiator in each compartment having a connection with said main; a ventilating duct for each compartment adapted to discharge therein fresh air adjacently to a radiator; means for choking back around the radiator, the 20 fresh air admitted through said ducts; a valve in the connection of each radiator with

said main; and independent means for each compartment for actuating each valve in accordance with the temperature of the compartment; substantially as shown and described.

25 6. In an incubator divided into a series of compartments arranged vertically with reference to each other, of a common main for delivering heating fluid; a vertical flue from said main; a separate lateral extension from the vertical flue extending into each compartment; a ventilating duct for each compartment adapted to discharge therein fresh air adjacently to said lateral extension; and 30 means for choking back around said extensions the fresh air admitted through said ducts; substantially as shown and described.
